UNITED STATES PATENT OFFICE.

WILLIAM R. LOVE, OF ARMOUR, NORTH CAROLINA.

COIN-CONTROLLED MECHANISM FOR DISPENSING APPARATUS.

Original application filed October 28, 1919, Serial No. 334,010. Divided and this application filed March 1, 1920. Serial No. 362,246.

To all whom it may concern:

Be it known that I, WILLIAM R. LOVE, a citizen of the United States, residing at Armour, in the county of Columbus and State of North Carolina, have invented a new and useful Coin-Controlled Mechanism for Dispensing Apparatus, of which the following is a specification.

This invention has reference to coin controlled mechanism for dispensing apparatus and its object is to provide means whereby accessible manipulating means may be rendered active to dispensing apparatus on the insertion of an appropriate coin.

15 This application is a division of my application Serial No. 334,010, filed Oct. 28, 1919, for dispensing apparatus, in which apparatus containers and liquids deposited in such containers by the action of the apparatus, are delivered to customers on the proper operation of the apparatus rendered possible by the insertion of a suitable coin.

20 In accordance with the invention, a constantly accessible handle or manipulating lever is temporarily coupled to the dispensing apparatus by a suitable coin introduced through a coin slot or other proper entrance, but in the absence of a coin the manipulating lever may be moved without affecting the dispensing apparatus. Provision is made for arresting an introduced coin in the interlocking position to be released when the manipulating lever has been actively moved to a certain extent, such active movement being sufficient to cause the operation of the dispensing apparatus.

25 The invention will be best understood from a consideration of the following detailed description taken in connection with the accompanying drawings, forming part of this specification, with the understanding, however, that the invention is not confined to any strict conformity with the showing in the drawings, but may be changed and modified so long as such changes and modifications mark no material departure from the salient features of the invention as expressed in the appended claims.

30 In the drawings,

Fig. 1 is a face view of a portion of the casing of the dispensing apparatus, showing the coin-controlled mechanism partly in elevation and partly in section;

Fig. 2 is a section on the line 2—2 of Fig.

1, the section being on a larger scale than the showing of Fig. 1;

Fig. 3 is a section somewhat similar to that of Fig. 1 but drawn on a larger scale and omitting certain parts;

Fig. 4 is a section similar to that of Fig. 2 but of less extent and drawn on the scale of Fig. 3;

Fig. 5 is a view similar to but less extensive than that of Fig. 1 and showing in section some parts which are shown in elevation in Fig. 1, the scale being that of Fig. 3;

Fig. 6 is a section on the line 6—6 of Fig. 1;

Fig. 7 is a section on the line 7—7 of Fig. 6;

Fig. 8 is a perspective view of a one-way gravity latch for operating the coin trip or stop lever;

Fig. 9 is a perspective view of the coin trip or stop lever.

Referring to the drawings, there is shown a portion of a casing 1 having a forward extension 2 surmounted by a table or shelf 3 forming the cover of the extension. Within the extension 2 there is a frame 4 including end members 5, 6, respectively, near the bottom of which there is mounted a rod 7 upon which there is supported the lower end of a rock lever 8 rising upwardly through the frame 6 and through a slot 9 in the shelf 3. The slot 9 is relatively narrow and extends from front to rear of the shelf 3 so as to serve as a guide for the lever 8 which rises above the shelf 3 into accessible position and terminates in the handle 10 which may be readily grasped by the hand. The slot 9 is covered by a slide 11 mounted in guides 12 and this slide is of sufficient length to always cover the slot 9 in either extreme and all intermediate movements of rocking of the lever 9. Also mounted on the rod 7 and located immediately to the rear of the lever 8, in the normal position of the parts, is another substantially upright lever 13. The lever 13 is provided with a side entering slot 14 with a downwardly slanting bottom wall 15, the slot 14 with the bottom wall 15 constituting a gravity track or guideway for a coin 16 utilized to serve as a connection between the levers 8 and 13. The lever 8 carries on the face toward the lever 13 a hook-shaped lug 17 with the hook end spaced

away from the corresponding face of the lever 8 to enter an inset portion 18 of the slot 14, so that the hook 17 is out of the path of a coin rolling on edge downwardly 5 through the slot 14 along the slanting wall 15, the space between the hook-shaped lug 17 and the corresponding faces of the lever 8 forming a socket to receive the coin 16. The hook 17, where in line with the travel 10 of the coin 16 through slot 14 has a slanting bottom portion 19 conforming to the slant of the surface 15.

Carried by and depending from the shelf 3, within the forward extension 2 of the casing 1, is a coin chute 20 which may be of approximately quadrant curvature although such particular shape is not obligatory. The upper end of the coin chute 15 may be approximately level with the shelf 20 3 and the lower end is presented into close relation to the entering end of the slot 14 when the lever 13 is in its rearmost position so that at such time a coin deposited in the coin chute through the coin slot 25 will gravitate into the slot 14 in the lever 13 and roll along the wall 15 into the hook 17, so that by providing means for stopping the coin in engaging relation with the hook 17, the levers 8 and 13 are locked together so long as such conditions prevail. Then by grasping the handle 10 and pulling forwardly on the lever 8, the lever 13 is forced to participate in the movement 30 of the lever 8 because the two levers are locked together by the inserted coin. Ordinarily the levers 8 and 13 are held in the retracted position shown in Fig. 2 by a spring 21 in the frame 6.

Connected to the lever 13, by a pivot 40 pin 22, is a pull bar 23 constituting a connecting link between the lever 13 and the dispensing mechanism of the machine, so that whenever a proper coin is inserted and the lever 8 is pulled forwardly, the pull 45 bar is actuated correspondingly and the dispensing operation takes place.

Entering the slot 14 in the lever 13 and located high in said slot so as to be above a coin traveling therewith is a lever 24 50 with a nose portion 25 extending along the slot 14 near the upper end thereof toward the discharge end of the chute 20. This nose end of the lever has a curved lower face 26 conforming generally to the peripheral curvature of the coin 16. The curved face 26 at the end remote from the nose 25 merges into a depending tongue 27 55 of such length as to be normally in the path of the coin 16 and thus arrest the coin in the slot 14 so long as the lever maintains its normal position, said normal position being determined by a spring 28 fast at one 60 end to the lever 13 and at the other end engaging one arm 29 of the lever 24, such arm being that remote from the nose 25 and

said nose then engaging the upper end of the slot 14.

That end portion of the frame 6 remote from the chute 20 is provided with a cross piece 30 on which is pivotally mounted a gravity latch 31 having angularly related edges 32 in the path of the arm 29 of the lever 24, so that when the lever 13 is pulled forwardly by the lever 8 when locked to it, the arm 29 will ride over the latch 31, without rocking the lever 24 to an extent to carry the tongue 27 out of the path of the held coin 16, but on the return movement the gravity latch 31 is held by a pin 32a, or otherwise, thus causing the lever 24 70 to rock and thereby release the coin to gravitate downwardly along the slanting wall 15 and so escape from locking relation to the two levers 8 and 13. As soon as the arm 29 of the lever 24 has passed the latch 31, the spring 28 returns the lever to its original position into the path of a coin entering the slot 14 by way of the chute 20.

The entering end of the coin chute 20 90 is provided with a cut-off plate or strip 33 connected to a link 34, see Fig. 6, and this link is connected to one end of a rock lever 35, which, in turn, is connected by a link 36 to one end of another rock lever 37, 95 mounted on a fixed part of the frame of the machine. The pull bar 23 is pivoted to that end of the lever 37 remote from the link 36, so that when the pull bar is operated by the lever 8 so as to move the lever 13 through the intermediary of an 100 inserted coin, the entrance of another coin into the coin chute 20 is prevented by the passage of the slide 33 across the coin chute. On the return of the lever 8 to its first position the chute 20 is again freed for the 105 insertion of another coin. In this way there is no danger of clogging the machine in the attempt to put two or more coins in the machine at one time.

What is claimed is:

1. In a coin controlled mechanism for dispensing apparatus, a manipulating lever accessible to a customer, another lever associated with the first-named lever and provided with a coin passage therethrough, a coin stop carried by the second lever, coin holding means carried by the first lever and movable into the path of a coin traversing the passage through the second lever, a coin chute for directing the coin into such passage for positively locking the levers together, said stop being actuated to release the coin during the return movement of the locked levers for unlocking said levers.

2. In a coin-controlled mechanism for dispensing apparatus a manipulating lever accessible to a customer, another lever mounted to move about the same axis as the first lever and provided with a coin passage there-

through in a plane transverse to the plane of the movement of the levers, coin engaging means carried by the manipulating lever and transversely entering the slot in the second lever to receive a coin traversing said slot, whereby said levers are positively locked together, and connections from the second lever to dispensing parts to be actuated.

3. In a coin-controlled mechanism for dispensing apparatus an accessible manipulating lever rockable about an axis, another lever mounted on the same axis with the two levers capable of independent or joint movement and the second lever being connected to dispensing apparatus, said second lever having a coin passage laterally therethrough and provided with a slanting bottom to the passage, a stop lever for a coin carried by the second lever and entering the passage in the path of coins traversing the passage, means on the first lever for connecting the levers through the intermediary of an inserted coin, and trip means on a fixed portion of the apparatus and located in the path 25 of the stop lever for causing the release of an inserted coin.

4. In coin controlled mechanism for dispensing apparatus a manipulating lever, another lever associated therewith and connected to dispensing mechanism, the second lever having a coin passage therethrough with a downwardly slanting bottom, means carried by the first named lever to engage a coin in the second named lever to lock the levers together, a stop lever for an inserted coin and carried by the second lever normally in the path of the inserted coin to arrest the movement of the coin through the lever, and a one-way latch on the fixed part 40 of the mechanism for engaging the stop lever to move it out of the way of a coin to permit the escape of the coin from engagement with the levers.

5. In a coin controlled mechanism for dispensing apparatus a manipulating lever accessible to a customer, another lever associated with the first lever and the latter being movable with or without the second lever, connections between the second lever and the dispensing apparatus with which the coin controlled mechanism is connected, a coin chute leading to the second lever, a slide for opening and closing the chute, and lever and link connections between the second lever and the slide to cause the closing of the chute by the slide while the manipulating lever, with the second lever attached thereto, is being actuated.

6. In a coin-controlled mechanism for dispensing apparatus, a manipulating means accessible to a customer and comprising a rockable lever, another lever associated with the first-named lever and provided with a recess constituting a conduit for a coin, the first-named lever having a

lug movable into the coin conduit of the second lever in position to engage that side of a coin within said recess which is next to the second lever to positively lock the levers together, a pivoted stop member 70 carried by the second lever and normally located within the path of the coin, and means in the path of the stop means when the levers are cooperatively moved to cause the release of the coin when the manipulating lever has reached a predetermined point on the return stroke of said lever.

7. In a coin-controlled mechanism for dispensing apparatus, a manipulating lever accessible to a customer, another lever associated with the first-named lever and having a coin passage therethrough, a coin check carried by the second lever in normal position to arrest the movement of a coin through the coin passage in said second-named lever, a coin chute for directing the coin into the passage of the second lever to positively lock the levers together, and one-way gravity means in the path of the coin-engaging means and positioned to be 90 inactive to the coin stop means on the forward movement of the levers and to engage the coin stop means on the return movement of the levers to release the coin.

8. In a coin-controlled mechanism for dispensing apparatus, a manipulating lever accessible to a customer, another lever pivoted to swing about the same axis as the first-named lever and provided with a coin passage therethrough, a lug on the first-named lever adapted to project through the coin passage and having a laterally turned end spaced from said lever to form between said lug and lever a socket in which a coin is adapted to be seated, and means for temporarily retaining the coin in said socket whereby said levers are positively locked together.

9. In a coin-controlled mechanism for dispensing apparatus, a manipulating lever accessible to a customer, another lever pivoted to swing about the same axis as the first-named lever and provided with a coin passage therethrough, a lug on the first-named lever adapted to project through the coin passage and having a laterally turned end spaced from the lever to form between said lug and lever a socket to receive a coin moving through said passage, means for retaining a coin in said socket, whereby said levers are positively locked together, and means for releasing the retaining means at a predetermined point in the operation of the locked levers.

10. In a coin-controlled mechanism for dispensing apparatus, a manipulating lever accessible to a customer, another lever associated with the first-named lever and provided with a coin passage therethrough, a lug on the first-named lever adapted to pro-

ject through the coin passage and spaced from the lever to form between said lug and lever a socket to receive a coin moving through said passage, and means in the 5 coin passage located in alignment with said socket and operable towards said socket for temporarily locking the coin in the socket during a predetermined movement of the levers whereby said levers are positively 10 locked together.

11. In a coin-controlled mechanism for dispensing apparatus, a pivoted manipulating lever accessible to a customer, a lug mounted on the side of said lever and having 15 an angular end portion spaced from the side of the lever, a second lever pivoted to swing about the same axis as the manipu-

lating lever and having a coin passageway extending transversely therethrough in a plane at right angles to the plane in which 20 the lever swings, said manipulating lever being swingable to bring the space between it and the end portion of the lug into alignment with said passageway in the other lever to conjointly receive a coin, and means 25 for retaining said coin temporarily in said passageway between the lug and the manipulating lever, whereby the two levers are locked together.

In testimony that I claim the foregoing 30 as my own, I have hereto affixed my signature.

WILLIAM R. LOVE.
